UNITED STATES PATENT OFFICE.

PHILIP CARPELES, OF MILWAUKEE, WISCONSIN.

DESIGN FOR A CORNER-IRON FOR TRUNK-TOPS.

SPECIFICATION forming part of Design No. 18,874, dated January 22, 1889.

Application filed December 21, 1888. Serial No. 294,330. Term of patent 7 years.

To all whom it may concern:

Be it known that J. PHILIP CARPELES, a citizen of the United States, residing at Milwaukee, in the county of Milwaukee and State 5 of Wisconsin, have invented and produced a new and original Design for a Corner-Iron for Trunk-Tops; and I do declare the following to be a full, clear, and exact description of the same, reference being had to the accompanying drawing, forming a part thereof.

The said drawing is a perspective view illustrating both the configuration and surface ornamentation of my design.

Respecting the configuration, the article is 15 primarily curved from one end to the other, and one half of this length is practically at right angles to the other half, each side presenting a succession of Moorish or horseshoe arches, $a a' a'' a''' a^4$ and $b b' b'' b''' b^4$, respectively, the adjacent ends of the intermediate arches being united or connected, so as to form together rings $c c' c''$, the exterior single ends of the outside arches, b and b' and a and a' , terminating in similar rings, $c' c''$. The 25 arches $a a' a'' a^4$ are practically of the same size; but the central arch, a^2 , on that side of my design is considerably wider. On the other side the end arches, b and b' , are of about the same width as the corresponding 30 arches $a a^4$ on the other side; but the three intermediate arches, $b' b'' b'''$, are of less width, the central arch, b^2 , being the narrowest of all.

Above the ring which unites each two of

the described arches is a plain surface, $d d'$, of a general V shape, except that its ends 35 are rounded to conform to the shape of the adjacent arches, and within each V-shaped space described the surface is cross-hatched, as shown at e , the cross-hatched surfaces on one side uniting in continuous lines with the 40 cross-hatched surfaces e on the other side:

What I claim is—

The design for a corner-iron for trunk-tops herein shown and described, the same being primarily curved from one end to the other 45 and one half of this length practically at right angles to the other half, each side presenting a succession of Moorish or horseshoe arches, the adjacent ends of the intermediate arches being united or connected, so as to form together rings, and the exterior single ends of the outside arches terminating in similar 50 rings, the central arch on one side being the narrowest of all and the adjacent arches on this side of greater width than this, but of 55 less width than the end arches, while the central arch on the other side is of the greatest width of all, and the adjacent arches on that side are of practically the same width as the end arches on that side, as set forth. 60

In testimony whereof I affix my signature in presence of two witnesses.

PHILIP CARPELES.
